Primary Examiner — Keith J Wilson(74) *Attorney, Agent, or Firm* — JCIP Global Inc.(57) **CLAIM**

The ornamental design for an airless spray gun, as shown and described.

DESCRIPTION

FIG. 1 is a perspective view of an airless spray gun showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings represent of a portion the airless spray gun that form no part of the claimed design.

1 Claim, 7 Drawing Sheets(56)
